UNITED STATES PATENT OFFICE.

EDWARD A. MARSH, OF NEWTON, MASSACHUSETTS, ASSIGNOR TO WALTHAM WATCH COMPANY, OF WALTHAM, MASSACHUSETTS, A CORPORATION OF MASSACHUSETTS.

REPEATER TIMEPIECE.

1,421,801.

Specification of Letters Patent.

Patented July 4, 1922.

Application filed June 13, 1921. Serial No. 477,046.

To all whom it may concern:

Be it known that I, EDWARD A. MARSH, a citizen of the United States, residing at Newton, in the county of Middlesex and State 5 of Massachusetts, have invented new and useful Improvements in Repeater Timepieces, of which the following is a specification.

The class of timepiece to which this invention relates is that of the so called "repeating watch," that is, one by which an approximation of the present time may be made known otherwise than by visual observation of the hands. The repeating watches 10 heretofore made have universally, so far as I am aware, given their time indications by audible signals, and have also been so built that the necessary so called "repeating mechanism" is superimposed on the time train. Such mechanisms also have been unable to give an exact time indication. Some repeating mechanisms have means for indicating hours only, and others for indicating fractional parts of the hour to as small a fraction 15 as five minute intervals, but none, so far as I am aware, have been able to indicate the time to intervals of one minute.

The prior practice of locating the repeating mechanism in a superimposed position 20 over the time train or mechanism, has caused watches of this type to be excessively thick. On the other hand the development of pocket watches, and the taste of users thereof, has been in the direction of thinness; and all 25 possible expedients have been used to make watches as thin as possible consistent with satisfactory timekeeping qualities. Thinness being such an important consideration, the extra thickness caused by the superimposed repeating mechanisms of the prior 30 repeating watches has greatly decreased the desirability of such watches.

My object in making the present invention has been, first, to produce a repeating watch 35 equally thin and having equally good timekeeping qualities with the best watches of other types; second, to produce a repeating mechanism which gives its signals indicating time to the sense of touch, and inaudibly, 40 thus enabling deaf and blind persons to tell the time for themselves as accurately as is usually done by normal persons; and third, to provide means for rendering time indications with a much closer approximation to

the present actual time than is accomplished 55 by the mechanisms heretofore used.

The manner in which these objects have been accomplished, and the nature and characteristics of the present invention, are fully explained in connection with the following 60 description of a particular watch embodying the invention, to which reference will now be directed.

In the drawings, Figure 1 is an elevation on a much enlarged scale of the back of a 65 pocket watch embodying my invention, the rear cover of the watch case having been removed.

Figure 2 is a section on the line 2—2 of Figure 1 looking in the direction of the 70 arrow on said line.

Figure 3 is a section on line 3—3 looking in the direction of the arrow on said line.

Figure 4 is a section on line 4—4, Figure 75 1, showing in plan view part of the repeating mechanism and particularly the means for placing and holding the swing frame in operative position with relation to the time indicating elements.

Figure 5 is a cross section on line 5—5 80 of Figure 1.

Figure 6 is an elevation of one of the time indicating elements or disks of the repeating mechanism.

Figure 7 is a view generally similar to 85 Figure 5 but showing the feed pawl in the unlocked position and showing also the stop which normally locks the feeler and driving pawl.

Figure 8 is a view similar to Figure 4 but 90 showing the swing frame in the minute-indicating position.

Figure 9 is an elevation of the assemblage 95 of time disks by itself as viewed from the front of the watch.

Like reference characters designate the same parts in all the figures.

The first of the before named objects is accomplished by placing the repeating mechanism in the watch case beside the time 100 mechanism, and in what may be roughly called, for the purpose of this description, the same plane with the time train; meaning by "same plane" in this connection that the repeating mechanism is substantially included within an extension of the space between the plates of the watch movement wherein the time train is confined. The case

of the watch is appropriately shaped to contain the time and repeating mechanisms in this relation. A case having a rectangular outline is suitable for this purpose, as shown 5 in the drawing, since it is adapted to contain the mechanisms handily, is adapted to the pocket of the wearer and has a pleasing appearance esthetically. The central or frame part of the case (case center) is indicated at 10 1, the front cover at 2, and the back cover at 3. It is to be understood that, although the drawings do not show it, a suitable opening is made in said front cover, over which is set a crystal, through which the hands of 15 the watch may be seen.

Brief mention only need be made of the time train and the other usual parts of the watch since these require no modification in principle, or in any other manner than possibly slight changes from common designs in the arrangement of some of the wheels of the train. 4 represents the pendant, 5 the winding and setting crown and 6 the guard ring swivelled to the pendant, all according 20 to any common or satisfactory arrangement. 7 represents the main spring barrel, and 8 a winding wheel meshing therewith for winding the spring and adapted to be driven by the winding stem in any usual way. 9 25 represents the main wheel, 10 the center pinion driven thereby, 11 the center wheel, secured to the center pinion either directly or by means of the center staff, 12 the third wheel, 13 the fourth wheel, 14 the escape 30 wheel, and 15 the balance wheel. Of these parts only the center staff, center wheel, and center pinion are shown in detail (Figure 2), for any showing of said parts, further than indication of their positions, is not 35 needed to enable the present invention to be understood and to be put in practice by those skilled in the art.

Referring to Figure 2, there is shown in association with the center staff 16, the usual 40 cannon pinion 17 for the minute hand, dial train 18, 19, and hour wheel 20; the latter terminating in a sleeve or hub 21 which carries the hour hand. The time disks or indicating elements of the repeater mechanism 45 are driven from the dial train, rather than directly from the time train, in order that they may be moved in exact synchronism with the hands when the latter are set; and for so driving them, the intermediate wheel 50 55 18 of the dial train meshes with a wheel 22, staked on a pinion 23 which turns about a stud 24 fixed in the pillar plate 25. The elements just referred to as "time disks" are preferably three in number, designated 26, 27, and 28. The first of these controls the 60 hour indication for the repeater mechanism, the second controls the indications for shorter intervals, for instance, five minute intervals, and the third controls the indications 65 for the shortest intervals, which are prefer-

ably minutes. On account of the functions which these disks perform as above stated they may be called for convenience of the present description, respectively, the hour disk, the five minute disk, and the minute 70 disk. The designation "five minute disk" for the disk 27 is not to be construed as a limitation in the function of this disk, however, for instead of controlling the indications for five minute intervals, it may equally 75 well be designed to control other intervals, such as those of ten minutes, quarter hours, and so forth, wherefore for the purpose of a broader functional definition it may be termed an "intermediate time disk". For 80 similar reasons the third disk 28 may be called the "short interval disk". One or the other of the last two disks may be omitted if desired and the remaining disk be designed to cause indication of any desired 85 time intervals less than an hour.

These disks are driven from the wheel and pinion combination 22-23 in the following manner. A staff 29 is mounted to turn in bearings in the pillar plate 25 and top plate 30, and is made in one piece with a pinion 31, or equivalently so combined with this pinion that it will be rotated when the pinion is driven. The wheel 22 meshes with said pinion, and the disks 27 and 28 are 90 made fast to a sleeve 32 which is made fast on the staff, as by fitting friction tight thereon, or otherwise engaged to rotate with the staff. The disk 26, on the other hand, is made fast to a hub or sleeve 33 which turns 95 freely on the staff and to which there is also made fast a gear wheel 34 meshing with the pinion 23. The wheels 18 and 22 are equal to one another, the gear ratio between 22 and 31 is equal to that between 18 and the 100 cannon pinion 17, and the gear ratio between 23 and 34 equal to that between 19 and 20, whereby the disks 27 and 28 are 105 rotated completely once in each hour and the disk 26 once in twelve hours. However, 110 other specific sizes and gear ratios may be adopted for this particular mechanism, provided the same result is accomplished.

The peripheries of all the disks are cut into steps of equiangular extent, those of the 115 hour and intermediate disks being twelve in number, corresponding to the hour and to the five minute indications of the watch dial, and spaced progressively at different distances from the center, with all steps of 120 equal radial height. The steps of the minute disk are sixty in number, but, unlike the hour and intermediate disks, are arranged in repeated groups or recurring similar series of steps, substantially as shown 125 in the drawing. Each group of five steps on this disk has an angular extent equal to that of any one of the steps on the intermediate disk, and the individual steps of the group are at progressively different distances from 130

the center by equal amounts, while corresponding steps in all the groups are at the same distance from the center, whereby they indicate subdivisions in minutes of each five minute interval indicated by the intermediate disk.

Instead of the precise number and arrangement of steps in the intermediate and minute disks, other forms may conveniently be provided, as by giving the intermediate disk six steps, each corresponding to a time interval of ten minutes, and arranging the steps of the minute disk in groups of ten; or by making the number of steps in the intermediate disk any other divisor of the number of shortest interval units in the hour and the number of grouped short-interval steps equal to the complementary divisor. But, having regard to the customary manner of telling time, the arrangement shown is preferred to others.

Cooperating with the disks thus described, is a plunger 35 which is carried in a swing frame 36 and is adapted to move endwise in said frame, toward and away from the axis of the disks, preferably in line with a radius thereof. The frame is conveniently made as a plate formed in any suitable way with a part 37 of extra thickness at or near one edge, in which is a guideway 38 for the plunger, and with a sleeve 39 at or near the opposite edge, which provides a bearing for a stem 40. Said stem 40, besides having an important function, later described, is one of two pivots about which the swing frame may turn, and passes through a block 41 which is secured by screws 42 to the back of the pillar plate, and has a tubular extension 43 passing through the case center. The other, and alined, pivot which aids in mounting the swing frame (and has another function, later described) is a pin 44 seated in a block 45, secured to the pillar plate, and projecting into a bearing formed partly in the body of the swing frame and partly in a complementary bearing block 46 secured to the frame body. Both the stem 40 and pin 44 are capable of sliding endwise, and the pin is pressed against the adjacent end of the stem by a spring helix 47 which occupies the bottom of the socket in block 45 wherein the pin is seated, and is partly contained in a recess in the pin. This disposition of the spring allows a long spring to be used at this point with economy of space.

By virtue of its capacity for oscillative movement, the swing frame may be displaced or shifted to bring the plunger 35 over any one of the three disks; and it is so shifted by a shaft 48 passing through and having a bearing in a bushing 49 which is screwed into the case center. On the outer end of this shaft is a knob 50, or equivalent handle, by which it may be turned between

the thumb and finger of the operator; and on its inner end is a web or plate 51 carrying a crank pin 52 which fits freely a hole in a crosshead or slide 53 held in a guideway 54 in the upper edge of the swing frame. 70

Said shaft, with its web and crank pin, may be considered and called the swing frame shifter. The swing frame is set and retained in either one of its three operative positions by a detent 55 shaped to enter each of three notches 56, 57, and 58 in the web 51, which notches are so spaced that when notch 56 is brought by rotation of the shaft to receive the detent, the plunger is placed over the hour disk; when notch 57 is brought to receive the detent, the plunger is placed over the intermediate disk; and when notch 58 is brought to receive the detent, the plunger is placed over the minute or short interval disk. This detent is spring actuated, being formed or mounted on a spring arm 59 which is secured at one end by screws 60 in a recess in the edge of the pillar plate; and its faces, as also the complementary faces of the notches, are so much inclined to the line of pressure application by and to these faces when the shaft is turned in either direction, that the detent is thereby displaced from any notch which it may occupy at such times, although it opposes sufficient resistance to prevent any accidental displacement of the shifter or swing frame. 90

Conveniently the plunger is made of a flat thin bar sliding in the groove or guideway 38 of the swing frame. That end of the plunger which engages the disks is reduced in width to a narrow projection 61 in order that it may make contact with only the particular point of any disk which is in the position for giving a time indication. 100

A bowed spring rod or wire 62 is attached at one end to a stud 63, fixed on the forward face of the swing frame, and at its other end to a stud 64, fixed in the plunger, which projects through a slot 65 in the frame. 110 The tendency of this spring is to urge the plunger toward the time disks, but it is normally resisted, and the plunger held retracted and clear of the disks, by a pawl 66 projecting under a shoulder 67 at the side 115 of the plunger. Such shoulder is also the endmost one of a series of ratchet teeth 68, with which the pawl 66 cooperates to give time indications; and a holding pawl 69 also coacts with the same ratchet teeth. 120 Said holding pawl is formed on the end of a spring arm 70 which is rigidly secured at the opposite end by screws 71 to the rear side of the swing frame, wherefore the holding pawl is constantly pressed yieldingly 125 toward the plunger.

The pawl 66 is pivoted by means of a pivot stud 72 to a spring arm or bracket 73 which is secured by screws 74 to the back of the swing frame, the two spring arms 70 130

and 73 being somewhat similar in character and each being adapted to be so flexed as to withdraw the pawls 66 and 69, respectively, from engagement with the ratchet teeth of the plunger. On the pawl 66 is a tongue 75 which projects into the space between the pawl 69 and a finger 76 made as a part of the spring arm 70. The projections 75 and 76 are adapted to be moved in the same path, whereby when the pawl 66 is withdrawn from the plunger in the manner presently described, its tongue 75 strikes the finger 76 and likewise withdraws the holding pawl 69.

15 Also connected with the pawl 66 is a lever arm 77 which extends across the line of the stem 40 and pin 44 and is provided with a knob 78 at its end, which knob is slotted both longitudinally and transversely. The 20 longitudinal slot 79 in the lower part of this knob receives the upper end of pin 44 and permits the lever to be shifted endwise far enough to disengage it from the shoulder 67; a transverse slot or notch 80 between the 25 upper and lower parts of the knob receives two wipers 81 and 82 which project from opposite sides of the stem 40; and the notch 83 in the upper part of the knob receives the stem 40 above the wipers. The last-named notch permits the stem and lever to be assembled in the relation shown in the drawings and also permits the previously described endwise movement of the lever. A latch 84 is secured to the swing frame and 30 projects over the parts 85 of the knob lying at each side of the notch 83 when the lever occupies the position shown in Figure 1.

The stem 40 projects through the case center and is provided with a crown 86 on its end by 40 which it may be turned or moved endwise. When turned by the operator in either direction, one or the other of the wipers 81 or 82 is caused to wipe across the surface 87 or 88 of the knob 78 which bounds the notch 80, 45 and thereby to displace the lever 77 and pawl 66 away from the plunger 35. The same displacement of the knob shifts its jaws 85 clear of the stop 84, as shown in Figure 7.

The manner of use of the repeating mechanism thus described may now be understood; and in describing such use I will assume that the time disks 26, 27 and 28 are designed to show, respectively, hours, five minute intervals and minute intervals; and 55 that the indications are sought in the same order. Proceeding as thus indicated, the operator will first turn the shifter knob 50 until the notch 56 receives the detent 55. This action will place the plunger 35 over the 60 hour disk. Then the operator turns the crown 86 in either direction, thereby withdrawing the pawls 66 and 69 clear of the plunger 35. The latter being left unsupported, is then projected by the spring 62 until 65 the point on its lower end brings up against

the part of the hour disk which is directly beneath it. If we assume that the time of day is 11:46 a. m., for example, then the part of the disk which thus arrests the plunger is some point in the next to the lowest step, 70 which is designated 26^a in the drawing.

The movement given to the pawl lever 77 has shifted the parts 85 clear of the latch 84, wherefore simultaneously with the descent of plunger 35, the knob 78 and stem 40 are 75 raised by spring 47 until the knob is arrested by the hub 39. Thereafter the operator pushes down upon the crown 86 until the lever is arrested by the bearing block 46, and in so doing raises the plunger through the 80 engagement of pawl 66 with one of the ratchet teeth 68. The distance between the hub 39 and bearing 46 is so limited with respect to the length of the knob that the movement thus given to the plunger is equal to 85 or greater than the length of one of the ratchet teeth and less than the length of two such teeth; and such teeth are spaced equally to the radial spacing of successive steps in each of the disks. When the crown is released after having been pressed upon, the spring 47 again raises the arm 77, stem 40 and crown 86, correspondingly lowering the pawl 66 and causing it to slip over the next ratchet tooth beneath, for the plunger is held 95 stationary by the holding pawl, and enough space exists between the projections 75 and 76 to permit displacement of the driving pawl in passing over a ratchet tooth without disengaging the holding pawl. So long as 100 the driving pawl is engaged with any ratchet tooth above the lowest tooth or shoulder 67, the parts 85 of the pawl arm are held back clear of the latch 84, wherefore the arm may be oscillated by the operator pushing on the 105 crown and by the spring moving the crown outward, without hindrance. But when the action of spring 47 at last carries the pawl over the last ratchet tooth and under the shoulder 67, the parts 85 are pressed against 110 the latch 84 by the spring arm 73, and when the crown is next pushed upon, the abutments 85 pass the end of the latch and are carried under the latter by the pressure of the spring 73. No further endwise movement of the 115 crown is then possible, and the operator is thus informed that the plunger has been restored to fully withdrawn position. Having counted the number of pushes necessary to reach this condition the operator is informed 120 of the hour; that is, in the example assumed he has counted eleven pushes and he knows that the hour is eleven o'clock, or later, but not twelve o'clock.

It may be noted at this point that the 125 highest step 26^b of the hour disk is one space below the withdrawn position of the plunger, and that this step crosses the path of the plunger in the interval between one o'clock and two o'clock while the other steps are pro- 130

gressively nearer the center of the disk by equal amounts down to the twelfth or lowest step. Thus the distance of any step in the hour disk below the plunger, measured in 5 steps of the movement of the plunger, causes an indication of the current hour in terms of the time of day.

Having thus determined the time to the correct hour, the operator turns the shift 10 knob 50 to the mid position, which swings the plunger over the five minute, or intermediate disk 27, and repeats the operation of first turning the repeater crown and then pushing it in as many times as he finds that 15 it is free to move. In the suggested example, the ninth step, 27^a, below the highest one, 27^b, of this disk will be in the path of the plunger, which will make it necessary to push the stem nine times in order to retract 20 the plunger fully. Since the steps here represent five minute intervals, nine steps amount to forty-five minutes; and the operator is thus informed that the time is between forty-five and fifty minutes after 25 eleven o'clock. The steps of the five minute disk are each one step higher than corresponding steps of the hour disk, which results in the condition that when the highest step 27^b is in the path of the plunger, the 30 latter is unable to move downward far enough to result in any time indication. This condition is necessary because each five minute indication, to be correct, must come at or after the end of the five minute 35 interval which it designates, and no indication will be given with this disk prior to five minutes after the hour.

Finally, to determine the time to the nearest minute, the operator moves the shift 40 knob further around until notch 58 receives the detent 55 (Figure 8), thereby swinging the plunger into position over the minute disk 28. A repetition of the operations performed with the crown, first turning it and 45 then pushing it in as many times as possible, shows the number of time intervals elapsed since the end of the last preceding five minute interval, and this number is added to the indication derived from the five 50 minute disk. At the hour 11.46 the minute disk is in position to permit downward movement of the plunger by one step and restoration of the plunger by one push of the crown. As in the case of the intermediate 55 disk, the highest step of each group of steps on the minute disk lies so close to the retracted position of the plunger, when in the path thereof, as not to permit any appreciable movement thereof, wherefore 60 the impossibility of moving the crown to the full inward limit when manipulated in connection with the minute disk, informs the operator that less than one minute has passed since the end of the last five minute interval; while ability to push the crown forward 65

one, two, three, or four times, denotes that one, two, three or four minutes, respectively, have passed since that time point.

It will be readily appreciated that by making the intermediate time disk with six steps instead of twelve from the highest to the lowest point, ten minute intervals will be designated, and that correspondingly the minute disk would have six groups with ten steps or levels in each; or that other intervals may be provided for in the intermediate disk, and the steps of the minute disk correspondingly grouped, all within the principle of the construction and arrangement here illustrated and described. This principle includes the combination of two synchronously rotating disks or equivalent counters, one of which designates intervals of a predetermined length, and the other indicates subdivisions of those intervals. 85

It will be noted that in each disk, the highest step follows the lowest step abruptly, so that the beginning point of the former and the last point of the latter arrive simultaneously at the line of action of the plunger. In the case of the intermediate disk, which rotates through six degrees of arc per minute of time, and having regard to the fact that several seconds of time would usually be required for the operator to push in the 90 crown eleven times, a condition is liable to occur where the forward end of the highest step would interfere with the plunger before the latter could be fully retracted. This might happen if the repeater mechanism were operated within a few seconds before the even hour. To remove danger of the watch being stopped or injured in any respect by such interference, I may construct the intermediate disk substantially as shown 100 in Figure 6, with means for supporting the highest step in a yielding manner permitting it to spring backward (with respect to the direction of rotation of the disk). To this end the outer step 27^b is formed by a separate piece 90 having a narrow shank or neck 91 of such dimensions and quality that it is freely yielding and resilient. Preferably this piece is made of spring steel; and it is attached to the disk body in any convenient 110 manner, as by a dovetail joint shown at 92. The minute and hour disks may also be made yielding as to their highest steps, but as the distance through which the plunger must travel in order to clear the highest steps of the minute disk is comparatively short, and as the movement of the hour disk is very slow, this feature will ordinarily be unnecessary in those instances. 115

Various modifications in the form, construction, proportions, and placement of the parts and members of the repeater mechanism may be made without departing from the spirit of my invention. For instance, the edges of the disks may be made with 120

gradual differences of radius rather than with abrupt steps or shoulders; and more or less than three time disks may be provided in proper cases within the scope of the 5 claims. Further the term "disk," used in this specification to denote the time-indicating elements, is not necessarily confined in meaning to the precise form of the specific disks shown in the drawings; and the same 10 may be said as to the descriptive designations of other parts of the mechanism. Referring particularly to the crown 86, this may be considered, having regard to its function and result, as a "feeler," and so 15 called, since its movements under manipulation of the user gives to his sense of touch the required time indications.

Although in the foregoing explanation I have referred in some instances to the positions of the parts in relation to one another, and to the directions of movement of movable parts, in precise terms, I have done so simply for brevity and with reference to the position in which the watch is shown 20 in the drawings, and without intent thereby to imply any limits to my claim for protection.

A screw 94 is set into the back of the pillar plate near the free edge of the swing 30 frame. The head of this screw is slabbed off on each side and is located in a position which enables it to be turned so as either to overlap the swing frame or to clear the frame. When in the overlapping position 35 it holds the free edge of the frame close to the pillar plate and prevents the frame from swinging wide when the movement is removed from the watch case and the swing frame thereby relieved from the restraint of 40 the shifter.

What I claim and desire to secure by Letters Patent is:

1. A repeating watch comprising a time movement and a repeating mechanism operatively mounted side by side.

2. A repeating watch comprising a time movement, a case containing said movement and being extended laterally, and a repeating mechanism occupying the lateral extension of the case in the same plane with 50 said movement.

3. In a watch, a time movement including a hand-driving train adapted to be moved by setting the hands independently of said 55 time movement, and a repeating mechanism beside the time movement including a time element geared to said train to be actuated in unison therewith, whether in running or in being set, and means cooperating with 60 said element for giving invisible time indications.

4. In a watch, a time movement including a hand-driving train adapted to be moved independently of the movement for setting 65 the hands, and a repeating mechanism lo-

cated beside said movement and including a rotatable time indicating element, a gear train between said element and the hand-driving train and in the same plane with the latter for driving and setting said element in unison with the watch hands, and means complementary to said element for giving invisible time indications. 70

5. In a repeating watch, a plurality of time elements driven synchronously with the watch movement, each having points differently positioned according to successive fractions of a given time period, a movable feeler operable manually with reference to the points of said time elements, and means for bringing said feeler selectively into cooperation with either of said time elements. 75

6. In a repeater watch, a repeating mechanism comprising a plurality of time elements driven by the watch movement and 80 having controlling points differently positioned proportional to respectively different fractions of a given time period, mechanism operable manually in connection with individual ones of said time elements to give time indications through the sense of touch corresponding to the positions of said elements, and means whereby said mechanism may be shifted into position for coaction with either of said time elements successively. 85

7. A repeating mechanism in combination with a watch and comprising time disks rotatably mounted to turn about the same axis, gearing driving said disks from the watch 100 movement at respectively different rates of speed, one of said disks having controlling points differently distant from its axis and spaced to give hour indications, the other disk having controlling points differently 105 distant from its center and spaced according to fractions of an hour, a displaceable frame or holder, a plunger carried by said holder and adapted to be shifted by displacement of the holder into position for 110 engaging one or the other of said disks, and being movable in the holder toward and away from the adjacent point of the disk with which it is in cooperative relation, and 115 manually operative mechanism constructed to withdraw said plunger step by step from its engagement with the adjacent disk to a position clear of the outermost point of the disk; the number of steps required for so moving the plunger being proportional to 120 the distance of the point on the disk so engaged by the plunger from the outermost point of the disk. 125

8. In a repeater watch, a series of time disks comprising an hour disk, an intermediate disk, and a short interval disk, means driving said disks from the watch movement at such rates as to rotate the hour disk once in twelve hours and the other disks once every hour; the hour disk having twelve 130

- equiangular steps at different distances from the center progressively by equal increments, the intermediate disk having similar steps, the number of which is the divisor of sixty, 5 and the short interval disk having sixty steps which are arranged in groups similar to one another and in each group, of which the individual steps are progressively differently distant from the center by equal increments and the number of such steps in each group is a divisor of sixty complementary to the number of steps in the intermediate disk, and a feeler mechanism adapted to be operated in connection with said disks 10 for giving time indications according to the particular steps of said disks which are in position to cooperate therewith.
9. A repeater mechanism for time pieces comprising the combination of a time indicating element rotatably driven at a uniform rate of speed and having a series of equally spaced steps at distances progressively increasing by equal amounts from a base level, a plunger guided to move across the path 15 in which such steps travel, a spring acting on said plunger tending to move it toward that part of said element which crosses its prescribed path of movement, a pawl and ratchet mechanism, and a manually operable feeler connected with said mechanism for operating it, all arranged to withdraw said plunger from any position to which it may be projected by said spring in a series 20 of steps each substantially equal to the distances between successive steps of the time indicating element.
10. In a repeater mechanism for time pieces, the combination, with a time driven indicating element having a series of steps, 25 a plunger cooperative with said element and a spring arranged to project said plunger into contact with the temporarily adjacent step of said element, of control mechanism for said element comprising a driving pawl, a spring holder to which said pawl is pivoted and by which the pawl is pressed toward a part of said plunger, said part having a series of ratchet teeth complementary to the pawl and a shoulder of greater depth than 30 said teeth at the end of the series, an operating arm connected to said pawl, stops arranged normally to prevent oscillative movement of said arm, one of said stops and the cooperative part of the arm being so arranged that upon displacement of the arm in the direction permitted by yielding of said holder the arm is cleared of the last-named stop, an oscillative and endwise movable feeler stem arranged for manual operation, and means by which said stem in one of its movements is adapted so to displace the arm, and in another of its movements is adapted to swing the arm to cause driving of the plunger by said pawl.
- 35 11. In a repeater mechanism, a plunger guided to move in a given path and having a series of teeth and a shoulder of greater depth than said teeth forming the limit of such series, a holding pawl normally engaging one of said teeth, a driving pawl normally underlying said shoulder, a spring acting on said plunger pressing the shoulder thereof toward the driving pawl, resilient holders for the pawls arranged to press them toward the plunger and to permit their retraction against yielding resistance, an endwise movable and oscillative feeler, said driving pawl and feeler having interengaging parts so arranged that rotative movement of the feeler is adapted to withdraw the pawl from the plunger and endwise movement of the feeler is adapted to move the pawl in a direction for propelling the plunger, a spring acting upon said pawl tending to move it in the direction opposite to said propelling direction, and a stop arranged to prevent the spring induced movement of the pawl but so positioned as to be rendered inoperative when the pawl is displaced into the driving position.
- 40 12. A repeating mechanism comprising the combination with a number of time indicating elements adapted to indicate, respectively different intervals of time and each having differently positioned steps, of a plunger, a displaceable carrier for said plunger movable to place the plunger into cooperative relation with either of said elements in turn, and mechanisms associated with said plunger for causing its end to contact with the cooperatively adjacent element and for withdrawing it therefrom in a series 45 of definite steps.
13. A repeating mechanism as set forth in claim 12 and having also a shifter mechanism connected with said carrier and operable to place it in either of the specified positions and a detent arranged to retain said carried in each of said positions.
- 45 14. A repeater mechanism as claimed in claim 12 and including the combination therewith of a watch case, a shifter mounted upon the watch case and normally in engagement with said carrier for shifting it into either of its positions, but being disconnected therefrom when the mechanism is removed from the case with the timepiece movement, and a detent arranged to be engaged with the carrier to prevent free movement thereof relatively to the timepiece movement when the latter is removed from the case.
- 50 15. In a repeater mechanism, a time disk having a series of steps in which each successive step is farther distant than its predecessor from the center of the disk, there being an abrupt drop between the outermost and the innermost steps, combined with a reciprocating plunger arranged to be moved into and out of contact with the steps of

said disk for giving time indications, means for rotating said disk in a direction which brings the highest step of the disk into the line of action of said plunger immediately following the lowest step, and a spring arm fixed to the disk and carrying said highest step with provision for yielding oppositely to the direction of rotation of the disk.

16. A disk having its perimeter at successive equi-angularly spaced points progressively more distant from its center and having between its outermost and innermost points an abrupt drop, the outermost part of the disk being separate from the immedi-

ately adjacent part and being yieldingly mounted with ability to be displaced toward such part.

17. A time disk having its perimeter extending in an approximate spiral of progressively increasing diameter to its outermost part, the extreme outermost part of the disk being a separate piece having a spring shank secured to the body of the disk and adapted to yield in the plane of the disk.

In testimony whereof I have affixed my signature.

EDWARD A. MARSH
